Des. 225,141
Patented Nov. 21, 1972

225,141

MAGAZINE TREE

Hugh C. Acton, Ross Township, Kalamazoo County,
Mich., assignor to The Vecta Group, Inc., Kalamazoo,
Mich.

Filed Oct. 30, 1970, Ser. No. 25,735

Term of patent 14 years

Int. Cl. D6—99

U.S. Cl. D6—20

Fig. 1

Fig. 3

Fig. 4

FIG. 1 is a side elevational view of a magazine tree embodying my new design;

FIG. 2 is a top view thereof;

FIG. 3 is a bottom view thereof;

FIG. 4 is a top view disclosing the magazine support arms on one side of the vertical support post; and

FIG. 5 is a bottom view of the magazine tree with said arms in the position illustrated in FIG. 4.

I claim:

The ornamental design for a magazine tree, as shown.
